1

Genus and species: The avocado cultivar of this invention is botanically identified as *Persea americana* Mill.

Variety denomination: The variety denomination is 'BL516'.

BACKGROUND OF THE INVENTION

The invention relates to a new and distinct variety of avocado tree named 'BL516'. The new avocado variety originated from a breeding program at the University of California, Riverside, for the development of new avocado varieties. 10

The seed that produced 'BL516' was collected in 1983 from open pollinated 'Gwen' (U.S. Plant Pat. No. 5,298) avocado plants. The exact pollen parent is unknown. Seeds were planted in a test planting area in Ventura County, Calif. to produce avocado seedlings in the spring of 1985. A single plant of 'BL516' was selected with initial evaluation occurring in May 1991. 'BL516' was first top-worked by grafting onto *Persea americana* seedlings in the spring of 1991 in Irvine, Calif. The first fruit from the trees was tested in June 1994. This initial and subsequent asexual propagation confirmed that the new variety is stable and the progeny remain true to type. 15

(57) **ABSTRACT**

'BL516' is a new and distinct variety of *Persea americana* tree. The variety exhibits an upright growth habit with strongly drooping branches; and forms pyriform, slightly obovate or occasionally rhomboidal shaped generally black-skinned fruit when ripe that lack shoulders and is well distributed around the tree. The fruit is comparable in size to that of the 'Hass' variety and matures slightly later than the fruit of the 'Hass' variety. 'BL516' fruit has yellow-green flesh of excellent eating quality that is free of obvious fibers. The 'BL516' variety forms leaves in greater quantity than the 'Hass' variety and displays moderate resistance to the *Persea* mite.

2

BRIEF SUMMARY OF THE INVENTION

'BL516' exhibits the following combination of characteristics compared to other known varieties:

- 5 (a) 'BL516' has an upright growth habit with strongly drooping branches.
- (b) 'BL516' has pyriform, slightly obovate or occasionally rhomboidal-shaped, generally black-skinned fruit when ripe that lacks shoulders and is well distributed around the tree. In general, fruit is comparable in size and matures later than fruit of the 'Hass' variety. The fruit has yellow-green flesh of excellent eating quality that is free of obvious fibers.
- (c) 'BL516' forms leaves in greater quantity than the 'Hass' variety.
- (d) 'BL516' displays moderate resistance to the *Persea* mite.

'BL516' can be distinguished from all previously known avocado varieties including 'Hass' (U.S. Plant Pat. No. 35), 'Gwen' (U.S. Plant Pat. No. 5,298), 'Sir Prize' (U.S. Plant Pat. No. 9,709), 'Lamb Hass' (U.S. Plant Pat. No. 9,573), 'N4(-5)' (U.S. Plant Pat. No. 14,238), '3-29-5' (U.S. Plant Pat. No. 14,239), and 'BL 5-552' (U.S. Plant Pat. No. 33,534) in view of its distinctive combination of characteristics.

'BL516' is believed to be well-suited for the production of quality avocados under commercial growing conditions.

BRIEF DESCRIPTION OF THE PHOTOGRAPHS

FIG. 1 illustrates typical unripe 'BL516' fruit (bottom row) compared to unripe 'Hass' fruit (top row). All fruit were harvested in Irvine, Calif. in January 2022.

FIG. 2 illustrates four typical mature leaves of the 'BL516' variety. Leaves were collected from mature 'BL516' trees in the fall of 2014.

FIG. 3 illustrates a four-year-old top-worked tree of the 'BL516' variety growing in Irvine, Calif.

DETAILED BOTANICAL DESCRIPTION

The following is a description of 'BL516' trees that were grown at experimental orchards in Irvine, Calif. unless otherwise indicated. The trees were approximately 2 to 17 years of age, and had been grafted on *Persea americana* seedling or clonal 'Dusa' rootstock. Where possible, comparison varieties were of approximately equivalent age. The comparative trees for the 'Gwen' variety, however, were mature and their exact age is unknown. Color information is designated with reference to The R.H.S. Colour Chart of the Royal Horticultural Society, London, England, 2001.

Tree:

Growth habit.—'BL516' is upright in growth habit with strongly-drooping branches compared to an upright habit with semi-drooping branches for the 'Gwen' and 'Lamb Hass' varieties; and upright and spreading habit with no drooping branches for variety 'N4(-)5'. Internode lengths on the shoot are mostly short, but occasionally intermediate, compared to mostly intermediate to short lengths for the 'Lamb Hass' variety, intermediate lengths for the 'Gwen' variety, and intermediate to long lengths for the 'N4(-)5' variety.

Height.—Averaging 4.5 m for fully mature trees, about 10-15-years old, which is similar to the 'N4(-)5' variety, compared to an average height of 4.4 m for the 'Hass' variety and 4.3 m for the '3-29-5' and 'Lamb Hass' varieties.

Width.—Averaging 3.3 m for fully mature trees, which is similar to the '3-29-5' variety, compared to an average width of 3.8 m for the 'N4(-)5' variety, 3.6 m for the 'Lamb Hass' variety, and 4.1 m for the 'Hass' variety.

Canopy volume.—A comparison of 'BL516' canopy volume to 'Hass' canopy volume is provided in Table 1. Volume was determined using a formula that includes tree height and the average canopy width taken at chest height from two trials, one in Irvine, Calif. and the other in Exeter, Calif. in the San Joaquin Valley. The trees were planted in 2013 on 'Dusa' clonal rootstock. Measurements (Table 1) were from mature trees, taken in Fall 2020. For the Irvine site, 'BL516' tree volume was approximately 45% of the canopy volume of Hass. The Exeter site provided similar results, in which the 'BL516' tree volume was again about 45% of that of Hass.

TABLE 1

A comparison of 'BL516' to 'Hass' trees 7 years after planting in terms of average canopy width, tree height and canopy volume.

Site	Variety	Canopy width (m)	Tree Height (m)	Canopy Volume (m ³)
Irvine	BL516	3.46 b	4.23 a	27.19 b
	Hass	5.08 a	4.27 a	60.62 a
Exeter	BL516	2.77 b	3.09 b	13.63 b
	Hass	3.58 a	4.47 a	29.83 a

Mean separation using Student-Newman-Keulstest at $P < 0.05$. The designations "a" and "b" shown for each comparison characteristic at each site indicate that the means are statistically different at the 95% confidence level. Two "a" value designations for a given comparison indicate that the means are not statistically different at the 95% confidence level. Each site analyzed separately. Tree numbers for each site: Hass, 3 trees; BL516, 15 trees.

15 Canopy width for individual trees was measured down the row and across the row and then averaged.

Canopy volume calculated using the following formula: (Height * (Average canopy width)) * 0.5236

Main stem:

Bark.—Substantially identical to that of the 'Hass', 'Gwen', 'N4(-)5', and '3-29-5' varieties. The new wood is smooth without corky lenticels. The old wood is corky in appearance as observed with most other avocado varieties and light brown or gray, RHS Greyed-Green Group 197D, in coloration.

Trunk size.—Trees average 49.1 cm in circumference, as measured at approximately 30 cm above the soil line, above the graft union and before major branching occurs, compared to an average circumference of 47.2 cm for the '3-29-5' variety, 57.8 cm for the 'N4(-)5' variety, 53.8 cm for the 'Hass' variety, and 51.7 cm for the 'Lamb Hass' variety.

Branch:

Color.—The color of a one-year-old branch is RHS Yellow Green 145A. The most recent fully-formed young shoot (flush) is also RHS Yellow Green 145A.

Smoothness.—The bark of a one-year-old branch is smooth.

Lenticels.—The lenticels of a one-year-old branch are conspicuous and are RHS Yellow Green 143A in color, while the lenticels of the most recent fully-formed flush are generally RHS Yellow Green 144A.

Young shoot (flush):

Intensity of anthocyanin coloration.—Strong, RHS Greyed Purple Group N186C; Underside is RHS Greyed Orange Group 175A. Young leaf surface is medium glossy.

Young shoot color of lenticels.—Not very conspicuous. Yellow to light green in color, generally RHS Yellow Green 144A. Lenticels are generally between 0.8 mm and 2.9 mm in length and are at a density of about 17 per cm². Young shoot main color is RHS Yellow Green Group N144A.

Mature leaf:

Shape.—Generally lanceolate to somewhat oval with an acute tip and an acute base. The shape is substantially the same as that of 'N4(-)5' and '3-29-5' varieties, compared to more oval to somewhat lanceolate for the 'Hass' variety, or more oblong lanceolate to lanceolate for the 'Gwen' variety. Leaf base is acute and leaf apex is mostly acute, which is substantially similar to 'Gwen' and 'N4(-)5' compared to the 'Hass' or '3-29-5' varieties, which have a more intermediate to acute apex. The leaf blade of 'BL516' does not twist along its entire length, nor does the apex of the leaf exhibit twisting.

Seed:

Length.—Approximately 4.1 cm.

Width.—Approximately 3.4 cm.

Weight.—Approximately 31.2 grams. This is smaller than the 'Hass', '3-29-5', and 'Lamb Hass' varieties measured, which averaged 31.6 grams, 43.2 grams, and 35.1 grams respectively.

Shape (in longitudinal section).—Almost equally tending towards ellipsoid or broadly ovate compared to the 'N4(-5)' and 'Gwen' varieties, which are spheroid; the 'Hass' variety, which is variable but mostly ellipsoid; or the '3-29-5' variety, which is broadly obovate.

Shape (in cross section).—Generally circular.

Color of seed coat (fresh).—Ranges from RHS Greyed Orange Group 166A, RHS Greyed Purple Group 183A, RHS Greyed Purple Group 183B, RHS Greyed Orange Group 177A, RHS Greyed Purple Group 186C, to RHS Greyed Purple Group 187A.

Cotyledon color.—Generally ranges from RHS Orange White Group 159A and RHS Orange White Group 159B to Orange White Group 159C.

Productivity: Generally comparable to that of the 'Hass' variety, but with perhaps less precocity. Table 2 provides a comparison of cumulative fruit count, yield, average fruit size and alternate bearing index. Fruit is borne on the inner branches of the tree, however, and more protected from sun, wind or other weather damage. 'BL516' has lower alternate bearing tendency than the 'Hass' or 'Lamb Hass' varieties, similar to the '3-29-5' variety.

TABLE 2

A comparison of 'BL516' to 'Hass' trees 9 years after planting in terms of cumulative fruit count, yield (kg), average fruit size and alternate bearing index.

Site	Variety	Cumulative Fruit Count	Cumulative Weight (kg)	Average fruit size (g)	Alternate Bearing Index
Irvine	BL516	610.5 a	131.2 a	213.5 a	0.59 a
	Hass	659.3 a	144.9 a	220.0 a	0.76 a

TABLE 2-continued

A comparison of 'BL516' to 'Hass' trees 9 years after planting in terms of cumulative fruit count, yield (kg), average fruit size and alternate bearing index.

Site	Variety	Cumulative Fruit Count	Cumulative Weight (kg)	Average fruit size (g)	Alternate Bearing Index
Exeter	BL516	210.1 a	29.7 a	165.4 a	0.33 b
	Hass	389.0 a	53.9 a	138.6 a	0.81 a

Mean separation using Student-Newman-Keulstest at $P < 0.05$. The designations "a" and "b" shown for each comparison characteristic at each site indicates whether the means are statistically different at a 95% confidence level. Two "a" value designations for a given comparison indicate that the means are not statistically different at a 95% confidence level. Each site analyzed separately. Trees planted in 2013 on 'Dusa' clonal rootstock. Tree numbers for each site: Hass, 3 trees; BL516, 15 trees. Alternate Bearing Index year-5 to year-10 were used to calculate I, based on the calculation of Hoblyn et al. (1936): $I = (l/n) \times [l^2/y - y/(y + y)]$, where y_i is the observed yield in an ordered series of size n , and $y_i - y_{i-1}$ is the absolute difference between successive yields. Alternate bearing index calculated beginning with year 4.

Hardiness: Generally comparable to the 'Hass' variety (USDA hardiness zone 9-11). For comparative purposes, the '3-29-5' is considered to be more cold-tolerant whereas the 'Gwen' and 'N4(-5)' varieties are considered to be less cold-hardy.

Market Use

'BL516' avocados have excellent eating-quality and can compete favorably with the 'Hass' variety for both fresh retail and food service markets. The fruit exhibits post-harvest handling and storage traits that allow it to be treated in much the same manner as the 'Hass', '3-29-5', and 'Lamb Hass' commercial varieties.

The narrow, upright canopy makes the 'BL516' variety a candidate for high-density or hedge-row avocado plantings. Tree size and shape are also desirable qualities for backyard growers. 'BL516' thus also has retail nursery value.

The B flowering-type indicates that it can be a useful pollinizer for 'Hass', 'Reed', '3-29-5', 'Lamb Hass', and other flowering group A-type commercial varieties.

What is claimed:

1. A new and distinct variety of avocado tree named 'BL516', substantially as illustrated and described herein.
